Primary Examiner — John Windmuller*Assistant Examiner* — John R Yeh(74) *Attorney, Agent, or Firm* — Ashley Law Firm P.C.; Stephen S. Ashley, Jr.(57) **CLAIM**

I claim the ornamental design for a handle, as shown and described.

DESCRIPTION

FIG. 1 is a perspective view of a handle according to the invention;

FIG. 2 is a left side view of the handle apparatus of FIG. 1;

FIG. 3 is a right side view of the handle of FIG. 1;

FIG. 4 is front elevation of the handle of FIG. 1;

FIG. 5 is a rear elevation of the handle of FIG. 1;

FIG. 6 is a top plan view of the handle of FIG. 1; and,

FIG. 7 is a bottom plan view of the handle of FIG. 1.

The broken lines in the figures represent portions of the handle that form no part of the claimed design.

1 Claim, 4 Drawing Sheets(56)
